UNITED STATES PATENT OFFICE

WILLARD J. WOODCOCK, OF BROOKLYN, NEW YORK

STOKER

Application filed November 6, 1926. Serial No. 146,582.

This invention relates to improvements in furnaces and in particular to furnaces employing underfeed stokers for boilers and the like.

5 It is a primary object of the invention to provide a fuel retort and grate mechanism which may be easily installed in or removed from a furnace without removing any of the walls of the furnace, but which instead may 10 be passed into the combustion chamber through the usual doors provided in furnaces of this type.

It is a further object to form the fuel supporting units and fire grate units of detachable sections any of which may be readily removed from the fire chamber, as for replacements or repairs.

Other objects relate to provisions for more satisfactory feeding and burning of the fuel, 20 protecting the units against being burned out, and reducing the amount of attention required by providing for the ready removal of ashes and clinkers.

These and other objects will appear more 25 fully from the following specification when considered in connection with the drawings in which:

Fig. 1 is a vertical transverse sectional view of a furnace constructed in accordance with 30 my invention, parts being in elevation.

Fig. 2 is a longitudinal sectional view of the construction shown in Fig. 1, taken substantially on the line 2—2 of Fig. 1.

Fig. 3 is a plan view of the furnace, parts 35 being removed and parts being in section and being taken substantially on the line 3—3 of Fig. 2.

Fig. 4 is a perspective view of one of the 40 vertical retort forming sections showing a removed grate unit and tuyère.

Fig. 5 is a perspective view of one of the bars forming the grates.

Fig. 6 is a transverse sectional view of a 45 grate bar taken substantially on the line 6—6 of Fig. 1.

Fig. 7 is a bottom plan view of one of the tuyères, and

Fig. 8 is a front elevational view, parts 50 being in section, showing a modified form of my invention.

It has heretofore been the practice in installing underfeed stokers for boilers to entirely dismantle the furnace by removing some of the fire-brick walls before the feeding mechanism and fuel supporting and grate mechanism could be introduced into the combustion chamber. This necessarily required a considerable length of time and a large amount of work as one wall of the furnace always had to be completely torn down and rebuilt in installing the mechanism. Furthermore when any portion of the retort or grate mechanism was injured, as for example by reason of the intense heat of the combustion chamber, it was necessary to put out the fires and remove the entire mechanism before the defect could be remedied.

I have overcome these difficulties according to the present construction so that within a period of a few hours the fuel supporting and burning elements of a furnace may be entirely removed and replaced with others or any part of the mechanism may be removed for replacement or repairs and the removed unit replaced or substitution made.

The furnace shown herein comprises the usual tubular boiler 10 (diagrammatically illustrated), the side walls 12 of the combustion chamber being formed with the usual fire-brick or other heat-resisting substance. The front wall of the furnace portions of which are indicated at 14 is formed with the usual access openings 16 normally closed by the doors 17, these openings permitting access to the fire chamber for the purpose of removing clinkers or for other purposes. A central opening is provided adjacent the lower portion of the front wall 14 through which the fuel is introduced by means of a plunger (not shown) in the usual manner where underfeed stokers are employed. The usual bridge wall 18 is placed at the rearward portion of the fire chamber 20 to deflect the hot vapors of combustion upwardly toward the boiler 10. The construction thus far referred to is of any usual or well known type and forms no part of my present invention.

For the purposes of my invention I provide a series of separable vertical sections

22 preferably formed as castings and which are designed to be placed in engagement one with the other and supported upon a suitable base 23 inclined slightly from the forward 5 to the rearward portion of the combustion chamber, as indicated in Fig. 2. These vertical sections are formed with central channeled portions 24 which portions, when the mechanism is installed in a furnace, form a 10 V-shaped fuel retort 25 as shown for example in Fig. 1. The sections 22 are provided with side openings 26 forming air passageways upon opposite sides of the retort 25 for providing passages for forced draft for the furnace as will appear more fully below. The 15 upper portions of the sections beside the channeled portions 24 are preferably formed of H section for receiving the removable tuyères 28 on each side of the central transverse partitions as shown in Fig. 4.

The tuyères 28 are formed with base portions 29 receivable within the side openings of the sections 22 and with the upper or outer head portions 30, air passages 31 extending 25 longitudinally along the tuyères and terminating in diverging air passages 32 preferably arranged on both sides of the tuyères. It is obvious that when a forced draft is introduced into the air passages 26 from any 30 suitable means that this draft will be emitted from the outlet openings of the tuyères at points along the upper side portions of the retort 25, thus assuring an intense heat being applied to the fuel prior to its passage onto 35 the grate bars hereinafter referred to. The tuyères 28 protect the sections 22 from the direct heat of the combustion chamber.

The end sections 22^a, 22^b, 22^c and 22^d forming the retort 25 are of modified construction 40 in order to provide a support for the fuel feeding mechanism in the lower portion of the retort and in order to force the fuel upwardly out of the retort. As indicated in Fig. 2, the sections 22^a to 22^d provide the inclined end wall 34 for the retort as well as the feed rod support 35. The rearward sections 22^c and 22^d are preferably closed at 45 their upper portion as indicated in Fig. 3 so that they will not be supplied with the forced air draft present in the remaining sections. The forced air draft enters the passageways 26 from the air inlet 36 provided with any suitable form of blower for giving the necessary draft. If desired openings 25 may be 50 provided on one or more of the sections 22 to permit a certain amount of air to pass beneath the grates to cool them and to promote combustion.

The sides of the vertical sections 22 are 55 provided with rod supporting hooks or loops 38 designed to receive the longitudinal rods 40 which extend outwardly beyond the forward and rearward ends of the combustion chamber and are provided with suitable nuts 60 for securing the sections together. The for-

ward ends of the rods may pass through openings in a face plate 42 in which there is provided the fuel opening for introducing fuel into the retort 25.

The grate construction for supporting the burning fuel at the sides of the retort 25 is 70 preferably formed of a series of separate grate bars 43 and 44 provided with hooked end portions 46 designed to be received over the rods 40 as indicated in Fig. 1. The grate bars are preferably reinforced for adequately supporting the outer or free ends thereof and at their highest points extend substantially to the same height as the tuyères 28, the bars, in the construction disclosed, being 75 inclined outwardly so as to give a certain fall to the fuel passing from the retort onto the grate bars although under certain conditions this inclination is not required. The upper surfaces of the grate bars are 80 preferably spaced and may, if desired, be provided with the usual openings permitting the passage of air upwardly through the grates to the ignited fuel.

The grate bars 44 are provided with extensions 44^a for supporting rotatable ash discharging members 48 and side plates 50. The members 48 are preferably formed as rectangular rotatable rods with circular portions supported in sockets in the extensions 44^a, the corners of the squared elements 48 being broken or otherwise irregularly formed to cause removal of a certain amount of ash when the elements are rotated. The side plates 50 supported in the outer sockets of the extensions 44^a are preferably inclined outwardly and upwardly so as to maintain the fuel on the grates and out of engagement with the side walls 12. The inclination of the plates 50 prevents them from being subjected directly to the radiated heat of the ignited fuel. The plates 50, as shown in the drawings, are apertured to permit the passage of air therethrough into the combustion chamber for maintaining the plates in a relatively cool condition and for promoting combustion 100 in the combustion chamber.

According to the above described construction it will be seen that the fuel supporting means and grates are formed of separate 115 units which may be readily passed inwardly into the combustion chamber through either the access doors 17 or through the fuel feeding door covered by the plate 42. The entire mechanism for supporting the fuel within 120 the combustion chamber including the retort forming sections 22, the tuyères 28, the grate bars 43 and 44 and side plates 50 may thus be removed for replacement in case the mechanism is severely damaged, or any one unit of the mechanism may be removed and replaced with a similar unit. The forced draft from the tuyères 28 adjacent the sides of the retort 25 assures an intense heat at 125 the point where the fuel is being passed from 130

the retort onto the grates, the downwardly inclined grate sections 43 and 44 and upwardly inclined side plates 50 assisting the passage of the fuel and ash toward the ash-re移ing element 48, the plates 50 preventing the fuel or ash from coming into contact with the side walls 12 of the furnace.

In Fig. 8 there is illustrated a modified form of my invention wherein the vertical sections 22', tuyères 28' and grate bars 44' are of the same construction as in the first form of my invention except that none of the grate bars are provided with the extensions 44''. In this form of the invention the upwardly and outwardly inclined side plates 50' are hinged adjacent their upper edges and are movable into engagement with or away from the outer edges of the bars 44', being controlled in this movement by means of any suitable crank arms as shown for example at 51'. The hinged side plates 50', which are preferably apertured as in the first form of the invention, thus serve to limit the outward movement of the fuel along the grate elements 44', the ash being removable between the plates 50' and grate elements 44' when the crank arms 51' are moved to permit the displacement of the side plates 50'.

While I have shown and described herein certain specific constructions, it is obvious that these are intended merely to illustrate the invention and that other forms may be employed so long as they fall within the scope of the appended claims. For example any desired number of sections 22 and aprons 44 may be employed dependent upon the size of the completed furnace, and since all of the main sections 22 are of identical construction smaller or larger furnaces may be built out of the same type of unit thus reducing the necessary supply of material on hand for original installations or replacements.

I claim as my invention:

1. In a furnace construction, a supporting structure comprising a plurality of separable vertical sections, grate bars removably supported by said supporting structure and extending outwardly therefrom, and side plates extending outwardly and upwardly from positions adjacent the outer edges of said grate bars for the purpose set forth.

2. In a furnace construction, a supporting structure comprising a plurality of separable vertical sections, grate members removably supported by said supporting structure, side plates extending outwardly and upwardly from positions adjacent the outer edges of said grate members and means for discharging ash at points adjacent the junction of said grate members and said side plates.

3. In a furnace construction, a plurality of hollow vertical sections formed with side chambers and a central channel portion providing air passages and a fuel retort, respectively, when said sections are placed in con-

tiguous relation in said furnace, said sections being formed with vertically arranged channels, the channels of adjacent sections coacting to form openings extending from said air passages to points without said sections, and removable tuyères removably mounted in said channels and formed with air ducts extending outwardly through the same for permitting the discharge of air from said air passages to points without said sections.

Signed at New York in the county of New York and State of New York this 5th day of November, A. D. 1926.

WILLARD J. WOODCOCK.
